UNITED STATES PATENT OFFICE.

OSWALD GWILLIM MANDERSON, OF FOOTSCRAY, VICTORIA, AUSTRALIA, ASSIGNOR OF
ONE-HALF TO BENJAMIN WILLIAMS, OF YARRAVILLE, VICTORIA, AUSTRALIA.

CIGARETTE-MAKING APPLIANCE.

Application filed June 5, 1925, Serial No. 35,080, and in Australia February 12, 1925.

This invention relates to a pocket, hand operated cigarette making device of the type in which a cylindrical mould is provided into which tobacco is placed and around which a paper is wrapped, means being provided to remove the paper and tobacco simultaneously from the mould.

Cigarette making devices have hitherto been suggested in which a tubular casing is fitted with an endwise movable internal sleeve around the upper end of which the cigarette paper is wrapped and into which the tobacco is introduced through a funnel attached to the tubular casing.

The object of the present invention is to provide an improved device which facilitates the production of shapely cigarettes and which also prevents tobacco projecting therefrom, and in addition provides a trap for some of the objectionable products of combustion and loose threads of tobacco.

With this object in view the present invention consists in a cigarette making device of the above type in which the mould has at its head a shallow flange the edges of which lie approximately flush with the palm of the hand when the mould is gripped between two fingers of the hand so as to facilitate feeding the tobacco from the palm of the hand into the mold.

In order to enable the appliance to be explained the drawings herewith will now be referred to, although there may be modifications of the details illustrated while keeping within the scope of the ensuing claims.

In these drawings each figure (except Figures 4, 5 and 11) is partly in longitudinal section to exhibit the interior.

Figure 1 shows a mould.
40 Figure 2 shows a mould cap.
Figure 3 shows the mould fitted with the cap.
Figure 4 shows a hand palm containing tobacco, and a mould head gripped between two of the fingers, the mould being ready to be filled.

Figure 5 shows a rod usable as a mould filler, tobacco packer, and mouthpiece former.

Figure 6 shows the hand holding the mould and the tobacco; the packer is also shown as used to fill the mould.

Figure 7 shows the mould, filled with tobacco, and having a cigarette paper partly wrapped round it.

55 Figure 8 shows the mould, still filled with

tobacco, but with the paper formed into a tube, and its end pushed into the mould and flanged (the latter being done with the rod) to form a trap.

Figure 9 shows the mould, but with the paper of Figure 8 longitudinally slid so that it projects from the mould ready to have tobacco pushed into it.

Figure 10 shows the next stage, all tobacco in the mould having been pushed into the paper, the pressure having slid the paper off the mould, thus making a cigarette.

Figure 11 is on a larger scale and shows a mouthpiece end view of Figure 8.

Figure 12 shows a protector plug, to be combined with the mould when it carries the cap and has the packer enclosed, the whole being then compact for carriage in a pocket. This protector will keep the packer and the appliance interior clean.

Figure 13 shows the several parts of the device assembled for carrying in the pocket.

A represents a tube of thin strong material, of any suitable diameter and cross section. This is the mould. B is a moderately narrow and particularly shallow flange at the head of the mould. The shallowness is essential; the flange is not a funnel primarily, but an abutment acting when the mould is gripped between two fingers C, D, as in Figure 4, to prevent the mould falling clear. In that position the flange is set practically flush with or lower than the palm E, in order to allow tobacco held in the palm to be easily pushed (in the directions shown by arrows)

80 across its edge into the mould bore A¹. It is found that only a very shallow flange will function thus; but one made as shown with a smooth concave under surface can be comfortably held flush (or lower than flush in some cases) with the surface of the said fingers and palm. The flaring flange, by its shallowness, facilitates return of any surplus tobacco on it to the palm after the mould is filled. The mould tube or part which will

100 have the cigarette paper wrapped round it, is advantageously made somewhat shorter than the length F¹ of the cigarette paper F, so that that paper when so wrapped around the mould will project at F² beyond the mould end A². This facilitates folding inward the paper edge F², to form a reinforced mouthpiece G (Figure 9). H is a detachable cap which will be fitted on the mould

105 before the latter is charged with tobacco; the

end of the cap is indented to form a part H' which fills the mould mouthpiece end for a short distance, and prevents the tobacco put into the mould occupying the area A^3 which 5 the part H' occupies; and therefore, when the cap is removed, there will be an empty space at A^3 . Into that space a part of the cigarette paper will be set, its location being seen in Figures 8 and 9. The cap H , as also 10 the flanged mould, will be made of one or more pieces of material. The simplest cap is in one piece, and pushes on; the simplest mould is of one piece of metal.

J is a mould packer of rod form having a 15 small end J^1 to be employed to push and pack tobacco into the mould, and having an opposite and larger end J^2 usable in forming the reinforced paper mouthpiece. The packer shown is of tapering form, and thus has different diameters at its ends. During the packing the small end J^1 is used, as it passes easily into the mould. This end is recessed, a suitable recess being marked J^3 , a packer so made keeping as a rule behind the tobacco, 20 instead of forcing its way through or past it. The large end J^2 is not a tight fit into the mould, but will enter easily even while it is surrounded by an inturned part of the cigarette paper; the large end is shown cupped.

30 The protector K is a short member having means to attach to the head of the mould, and shown as having a closed top K^1 , and a base of reduced diameter K^2 . This protector, when fitted on the mould with its base entering the flanged head, will hold securely and at the same time will cover the packer in the mould, so that the whole can be carried about with all interior parts safeguarded against entry of dirt. The protector base K^2 can be, if desired, inserted at the mouthpiece end of the mould to aid in making the paper fold or trap; the protector head K^1 can, if desired, be used as a plug instead of part H' of cap H .

To make a cigarette, grip the head of mould 45 A between two fingers with part of flange B overlapping and pressing the edge of palm E , letting the mould hang down, with a cap at its base.

50 Before or after so placing the mould, place enough tobacco to make a cigarette in the palm of the same hand; and, taking the packer in the other hand, slide the tobacco into the mould and pack the latter. Then take an ordinary hold of the mould, remove 55 the cap from its base, roll a cigarette paper round the mold and gum down the paper edge, letting part of the paper project from the mould base. Reduce this projecting part

in diameter, as by screwing it between the fingers so that it partly closes the mould end; 60 then push this part inward, making a circular flange of tucked or gathered paper. Press this flange against the tobacco if desired, or leave the flange oblique as shown. This will leave the tobacco uncovered centrally, for 65 draft purposes, but will provide a trap for some of the objectionable products of combustion, and loose threads of tobacco. Slide the paper tube partly off the mould as in Figure 9. Then press the large end of the packer into the mould head, forcing the contained tobacco out of the mould into the paper tube. When the tobacco reaches the trap aforesaid further pushing causes the paper to slide entirely off the mould, as well as to become 70 filled, the result being the cigarette required. Cigarette papers vary; some (as shown) are of single thickness throughout; others (which I may also use) are at the mouthpiece part stiffer (as by being waxed or by 75 having a thin strip attached of cork or other material to form a collar).

I claim:—

1. In a cigarette making appliance having a tubular mould, a cap having an indented 85 end to fit and remain in the mouthpiece end of the mould until the rest of the mould has been charged with tobacco.

2. In a cigarette making device of the character described, a tubular mould having a 90 flaring portion at one end constituting a shallow funnel with a smoothly concave under surface adapted to conform to the finger junction contour of a user's hand when the mould is held between the fingers, a removable 95 cap having an indented end to project into the mouth piece end of said mould, and a protector plug removably applicable to the other end of said mould, said plug having an end usable interchangeably 100 with said indented end and having also a reduced opposite end adapted to be projected into the mouthpiece end of the mould to tuck in the free end of a cigarette paper rolled about the mould.

3. In a cigarette making appliance having a flanged tubular mould, a protector plug having an end adapted to plug the mouthpiece end of the mould, and having an opposite end of reduced transverse area adapted 110 to tuck in a cigarette paper edge at the mouthpiece end.

In witness whereof I have hereunto set my hand.

OSWALD GWILLIM MANDERSON.
